UNITED STATES PATENT OFFICE.

WILLIAM HENRY FRANKLIN, OF RED LODGE, MONTANA.

POWER WASHING-MACHINE.

1,211,129.

Specification of Letters Patent.

Patented Jan. 2, 1917.

Application filed January 25, 1916. Serial No. 74,255.

To all whom it may concern:

Be it known that I, WILLIAM H. FRANKLIN, a citizen of the United States, and a resident of Red Lodge, in the county of Carbon and State of Montana, have invented a certain new and useful Improvement in Power Washing-Machines, of which the following is a specification.

My present invention relates particularly to certain new and useful improvements in power washing machines, the primary object thereof being to provide a small machine of this nature which may be set in a convenient and handy position, for instance, in a kitchen sink, for light washing and at the same time be self operating in order to do away with the constant attention and manual work necessary at present in machines of this character.

In carrying out these objects, and certain others which will hereinafter appear, I preferably utilize the construction to be now described with reference to the accompanying drawings, forming a part of this specification, and wherein—

Figure 1 is a side elevation of my improved machine. Fig. 2 is a horizontal section taken therethrough substantially on line 2—2 of Fig. 1. Fig. 3 is a central vertical section through the machine. Fig. 4 is a partial horizontal section taken substantially on line 4—4 of Fig. 3. Fig. 5 is a detail enlarged view of certain parts to be hereinafter described.

Referring now to these figures, I provide a machine, the casing A of which has a tapering body portion and a top, the latter of which is provided with a central opening and a flange A' surrounding said opening and providing for the reception of a cover or lid B, upon removal of which clothes to be washed may be introduced through the casing opening and into the space within the same, it being noted that the upper portion of the body of the casing A is provided with an inner surrounding wall indicated at C and provided with vertically disposed corrugations against which the clothes, in the operation of the machine, are rubbed and

cleansed.

Within the lower portion of the casing A and above its base D, is arranged a bowl shaped clothes receptacle E, opening upwardly, and the upper edge of which terminates slightly below the lower edge of the inner corrugated wall C before described, it

being noted that the corrugations which are provided in the bowl E and also those of the inner wall C, are closed at their ends by either flaring the same as indicated at e and e in Fig. 3, or by providing a covering strip as seen at C' in said figure.

As seen particularly in Fig. 3, the base D of the casing A, which is secured therein at a point substantially above the lower edge of the wall of the casing, is provided with a central opening and with a supplemental bearing piece D' secured thereto around said opening, said bearing piece being also centrally apertured for the reception of a depending shaft E' secured at its upper end to the central lower portion of the bowl E, and provided with an intermediate shoulder e' which rests upon the bearing plate or member D' and forms a substantial joint to prevent outflow of liquid from the interior of the casing A.

To the lower extremity of the shaft E' is secured a water wheel consisting of horizontally disposed superposed and connected disks F and F', the former of which is provided at its periphery with outstanding spaced and twisted impact buckets F², these buckets as well as the entire water wheel, being inclosed within a frame G secured to the bottom D of the casing, and provided therearound as shown best in Fig. 2, with a plurality of inclined openings G'.

Around the frame G just mentioned, is extended a nozzle tube H, one end of which is closed as for instance by a plug H' and the other end of which is extended outwardly through the lower portion of the casing wall below the casing bottom D and threaded as at H² for connection with a suitable water supply through, for instance, a flexible connecting pipe. The nozzle tube H just mentioned, is also provided in its length with a plurality of openings one of which is seen at H³ in Fig. 5, these several openings coinciding with the inclined openings G' of the frame G so as to introduce tangentially directed water jets within the frame G and against the buckets F² when connected with a water supply, the result being to rotate the bowl E through the connections described.

Thus in the operation of my improved washing machine, the clothes are introduced into the casing A in the manner described, and upon rotation of the bowl E through the means just previously described, are ro-

tated in a mass causing a thorough constant circulation of the cleaning fluid therethrough, and further causing the clothes to be rubbed both by the corrugations of the bowl E and against the corrugations of the inner wall C of the casing. In this way, a small, light, yet durable washing machine may be had, susceptible of ready manipulation and convenient transportation as by 10 means of handles I provided upon the casing A, and one which is capable of constant operation to thoroughly cleanse light washing without necessitating constant attention on the part of the operator or manual labor in 15 the washing operation.

I claim:—

1. In a washing machine of the character described, a casing having in its upper portion a rubbing surface, a fluid holding bowl shaped clothes receptacle disposed within 20 said casing below its said rubbing surface and opening upwardly to receive the clothes

introduced within the casing, and means for rotating the said bowl shaped receptacle whereby to move the clothes and fluid upwardly along the wall thereof and around within the casing and against the said rubbing surface. 25

2. In a washing machine of the character described, a casing having in its upper portion an annular rubbing surface, a fluid holding bowl shaped clothes receptacle disposed within said casing with its upper open end contiguous to and below the said rubbing surface to receive the clothes introduced within the casing, and means for rotating the said bowl shaped receptacle whereby to move the clothes upwardly therefrom and around within the casing and against the said rubbing surface, the said 30 bowl shaped receptacle also having a rubbing surface acting directly upon the clothes carried thereby. 35

WILLIAM HENRY FRANKLIN. 40
